CLAIM

What is claimed is the ornamental design for the hanging flashlight, as shown and described.

DESCRIPTION

FIG. 1 is a bottom perspective view of the first embodiment of the hanging flashlight showing my new design,

FIG. 2 is a front elevational view thereof;

FIG. 3 is a first side elevational view thereof;

FIG. 4 is a rear elevational view thereof;

FIG. 5 is a second side elevational view thereof;

FIG. 6 is a top plan view thereof;

FIG. 7 is a bottom plan view thereof;

FIG. 8 is a bottom perspective view of the second embodiment of the hanging flashlight showing my new design,

FIG. 9 is a front elevational view thereof;

FIG. 10 is a first side elevational view thereof;

FIG. 11 is a rear elevational view thereof;

FIG. 12 is a second side elevational view thereof;

FIG. 13 is a top plan view thereof; and,

FIG. 14 is a bottom plan view thereof.

The dashed lines within the figures are shown for illustrative purposes only and form no part of the claimed invention.
